US00D987622S

(12) **United States Design Patent** (10) **Patent No.:** **US D987,622 S**
(45) **Date of Patent:** **** May 30, 2023**

(54) **PORTABLE COMPUTER**

(71) Applicant: **Intel Corporation**, Santa Clara, CA (US)

(72) Inventors: **Gustavo Fricke**, San Jose, CA (US); **Mikko Makinen**, Santa Clara, CA (US); **Rand Lenroot**, Folsom, CA (US); **Christopher M. Moore**, Hillsboro, OR (US); **Saara Kamppari-Miller**, Hillsboro, OR (US); **Edward Morton Burdick**, Wiltshire (GB)

(73) Assignee: **Intel Corporation**, Santa Clara, CA (US)

(**) Term: **15 Years**

(21) Appl. No.: **29/729,266**

(22) Filed: **Mar. 25, 2020**

(51) **LOC (14) Cl.** **14-02**

(52) **U.S. Cl.**

USPC **D14/341; D14/315**

(57) **CLAIM**

The ornamental design for a “portable computer,” as shown and described.

DESCRIPTION

FIG. 1 is a top, front, right, perspective view of a portable computer.

FIG. 2 is a top, rear, left perspective view of the portable computer of FIG. 1.

FIG. 3 is a top view of the portable computer of FIG. 1.

FIG. 4 is a bottom view of the portable computer of FIG. 1.

FIG. 5 is a front view of the portable computer of FIG. 1.

FIG. 6 is a rear view of the portable computer of FIG. 1.

FIG. 7 is a right side view of the portable computer of FIG. 1; and,

FIG. 8 is a left side view of the portable computer of FIG. 1.

The broken lines in the drawings represent portions of the portable computer and form no part of the claimed design.
